SUBMARINE SIGNALING APPARATUS

Bertram M. Harrison, Newton Highlands, Mass.,
assignor to Submarine Signal Company,
Boston, Mass., a corporation of Maine

Application January 19, 1938, Serial No. 185,751
Renewed June 22, 1939

14 Claims. (Cl. 177—386)

The present invention relates to a submarine signaling device and more particularly to a device for transmitting and receiving compressional waves under water.

An object of the present invention is to provide an improved compressional wave sending and receiving device. A further object of the present invention is to provide such a device employing piezo-electric crystals. A further object of the present invention is to provide a compressional wave sending and receiving device particularly suitable for small echo sounding systems.

A form of the present invention is shown in the accompanying drawing in which Fig. 1 is a mid-sectional elevation and Fig. 2 is a cross-sectional plan view taken along the line II—II of Fig. 1.

As shown in the drawing the device is housed within a casing formed of a shell 1 having an external flange 2. The shell 1 is adapted to be secured within an aperture in the hull 3 of a vessel by means of a clamping ring 4 which is threaded on the outside of the shell 1 as shown and together with the flange 2 holds the unit firmly against the hull. Acoustic insulating material 5, such as rubber, is preferably inserted between the signaling unit and the ship's skin.

The lower end of the shell which is in contact with the outer water is closed by a diaphragm 6 having special characteristics to be described later. The diaphragm is held in place in the shell 1 between an inner flanged ring 7 abutting a shoulder 8 in the inside of the shell and an outer flanged ring 9 pressed against the diaphragm by the threaded ring 10 engaging internal threads in the shell 1.

The upper or inner end of the shell 1 is closed by a cylindrical cap 11 threaded into the shell 1. The cap 11 is firmly screwed down so that the shoulder 12 on the cap abuts the end of the shell 1, a rubber gasket 13 being interposed between these two elements.

The active member of the signaling device is mounted entirely within the cap 11. An inwardly extending flange 15 will be noted in the upper portion of the cap. To this flange is fastened a plate 16 by means of the screws 17. Secured to the plate 16 is a cylindrical mass member 18 having its lower end hollowed out so that it terminates in a cylindrical shell 19. Within this shell 19 are mounted piezo-electric crystals 20, for example of Rochelle salts, in such a manner as to make them as rigid and as nearly a part of the mass 18 as possible.

To this end the interior of the hollowed-out portion of the mass 18 is lined with insulating material such as a thin Bakelite disc 21 and a thin cylindrical strip 22. A group of crystals 20 are cemented by their ends against the member 21 which is cemented to the member 18. The crystals are firmly held against sidewise motion by slightly wedge-shaped pieces 23 of insulating material which fit firmly against the insulating strip 22 within the shell 19 and the crystals. In order to make the assembly still more rigid, the insulating blocks 23 are screwed to the shell 19 by means of the screws 24. The crystals 20 have their flat faces coated with metal foil as electrodes and are separated from each other by thin metallic strips 25 placed between adjacent crystals within those portions thereof which are within the shell 19. Thus, the lower ends of the crystals are free from contact with each other and with any solid element of the unit. Within the shell 19, however, the crystals and metallic strips are firmly clamped together whereby the crystals are rigidly fixed to the mass 18. The metallic strips 25 serve to connect adjacent crystals in series electrically. Electrical connection to the group of crystals is made to the external electrode of each of the end crystals of the group by means of the leads 26 and 27 which are brought upward through apertures in the insulating wedges 23, the mass element 18, the plate 16 and the upper end of the cap 11. In passing through the cap the leads 26 and 27 are preferably joined into a cable 28 which is made watertight with the cap 11 by means of suitable packing 29 and the clamping nut 30.

The interior of the signaling device is filled with a suitable sound-conducting medium, such as oil, through the filling aperture near the top of the cap 11 which may be closed by the plug 31. Considering, now, the acoustical features of the device according to the invention, it has already been mentioned that the piezoelectric crystals 20 are firmly fixed to the mass 18. The latter is made large enough so that it will act as a substantially infinite mass. The optimum height of the element 18 measured in the vertical direction, as shown in Fig. 1, is one-eighth of the wave length of the compressional waves within the material of which it is made at the signaling frequency or one-eighth plus any multiple of one-half wave length. Since the mass 18 is substantially infinite in effect, it will remain stationary and the portions of the crystals adjacent the mass will have zero amplitude of vibration while the lower ends of the crystals near the diaphragm

6 will have maximum amplitudes of vibration. The velocity of the free end of the crystals 20 at signaling frequencies of 10,000 cycles per second or over is too high to make it possible to obtain efficient transfer of power to the water directly. For this reason an impedance-matching transformer is required between the crystal and the water.

The crystal 20 is made one-quarter wave length long below the clamping line and, as has been mentioned, the element 18 is made one-eighth of a wave length long in order that it may have maximum mass reactance. The space between the crystal and the diaphragm 6 is made less than one-quarter wave length thick in order that no standing waves shall be present. The diaphragm 6 is made substantially one-quarter wave length in thickness in order to provide optimum impedance and loading on the crystal to transfer maximum energy from the crystal to the water. Moreover, the material of the diaphragm should preferably be chosen to have at one-quarter wave length thickness an impedance which is substantially the geometric mean between the crystal impedance and the water impedance.

Where the crystal is of Rochelle salt, I have found to be particularly well suited for the diaphragm material one of the phenolic condensation products, and especially a substance known under the trade name of Synthane Grade C. This substance has a specific gravity of about 1.35 and the velocity of compressional waves therein is about 9000 feet per second. In the arrangement described I have found that sufficient power output and sensitivity as a receiver can be obtained to make a highly efficient depth sounding system particularly for the measurement of relatively shallow depths when signaling frequencies of 10,000 cycles per second or over are employed.

Having now described my invention, I claim:

1. A submarine compressional wave sender and receiver comprising a housing open at one end, a mass element supported therein, a piezo-electric crystal having a longitudinal dimension and being rigidly fixed by one end to said mass element and a diaphragm closing the open end of the housing and positioned with its inner surface close to the free end of said crystal, said mass element having a longitudinal dimension parallel to the longitudinal dimension of the crystal and substantially equal to one eighth, the free portion of the crystal having a longitudinal dimension of one fourth and said diaphragm having a thickness of one fourth, all said dimensions being in fractions of a wave length of compressional waves of the signaling frequency in the respective materials.

2. A submarine compressional wave sender and receiver comprising a housing open at one end, a mass element supported therein, a piezo-electric crystal having a longitudinal dimension and being rigidly fixed by one end to said mass element, a diaphragm closing the open end of the housing and positioned with its inner surface close to the free end of said crystal, said mass element having a longitudinal dimension parallel to the longitudinal dimension of the crystal and substantially equal to one eighth, the free portion of the crystal having a longitudinal dimension of one fourth and said diaphragm having a thickness of one fourth, all said dimensions being in fractions of a wave length of compressional waves of the signaling frequency in the respective materials, and a compressional wave conducting liquid filling the space within the housing between the crystal and the diaphragm.

3. A submarine compressional wave sender and receiver comprising a housing open at one end, a mass element supported therein, a Rochelle salt piezoelectric crystal firmly fixed by one end to said mass element, a diaphragm closing the open end of the housing and positioned with its inner surface close to the free end of said crystal, said diaphragm being composed of a phenolic condensation product and having a thickness of substantially one quarter of a wavelength of compressional waves of the signaling frequency in the diaphragm material, and a liquid, compressional wave conducting medium within the casing filling the space between the free end of the crystal and the diaphragm.

4. A submarine compressional wave sender and receiver comprising a housing open at one end, a mass element supported therein, a Rochelle salt piezoelectric crystal firmly fixed by one end to said mass element, a diaphragm closing the open end of the housing and positioned with its inner surface close to the free end of said crystal, said diaphragm being composed of Synthane and having a thickness of substantially one quarter of a wavelength of compressional waves of the signaling frequency in the diaphragm material, and a liquid, compressional wave conducting medium within the casing filling the space between the free end of the crystal and the diaphragm.

5. A submarine compressional wave sender and receiver comprising a housing open at one end, a mass element supported therein, a Rochelle salt piezoelectric crystal firmly fixed by one end to said mass element, a diaphragm closing the open end of the housing and positioned with its inner surface close to the free end of said crystal, said diaphragm having a thickness of substantially one quarter of a wavelength of compressional waves of the signaling frequency in the diaphragm material and having an acoustical impedance which is substantially the geometric mean between the crystal and the water impedances, and a compressional wave conducting liquid within the casing filling the space between the free end of the crystal and the diaphragm.

6. A submarine compressional wave sender and receiver comprising an open ended cylindrical housing, adapted to be mounted in an aperture in the hull of a ship, a diaphragm of a phenolic condensation material closing the outer end of the housing and having a thickness of one quarter of a wave length of compressional waves of the signaling frequency in the diaphragm material, a cup-shaped cap closing the inner end of the housing, a metallic mass element having a thickness of one-eighth of a wave length secured within said cap, a plurality of piezoelectric crystals firmly secured to said mass element and having a free portion a quarter wave length long, and a compressional wave conducting liquid substantially filling all residual spaces within said housing.

7. A submarine compressional wave sender and receiver comprising a hollow cylindrical shell open at both ends adapted to be mounted in an aperture in the hull of a ship, a diaphragm closing the outer end of the shell, said shell having a threaded portion adjacent its inner end, a cup-shaped cap having a threaded portion adapted to engage said threaded portion of said shell and thereby to close the latter, and a plurality of piezoelectric crystals mounted within said cap, whereby the cap can be removed from the interior of the ship for inspection and replacement of the crystals.

8. A submarine compressional wave sender and receiver comprising a hollow cylindrical housing closed at one end by a compressional wave conducting diaphragm and at the other end by a cap member having concentrically mounted therein a cylindrical mass member terminating at the end facing the diaphragm in a cup, a group of rectangular prismatic piezoelectric crystals mounted in said cup with vibrational axes parallel to the axis of said mass member and means for firmly holding said crystals in said cup including a plurality of wedges of insulating material shaped to fit tightly between the rim of the cup and the crystals.

9. A submarine compressional wave sender and receiver comprising a hollow cylindrical housing open at one end, a compressional wave conducting diaphragm having a thickness of substantially a quarter wave length at the signaling frequency closing the open end of the housing, a quarter wave length vibratory piezoelectric crystal means loaded at one end by an effectively infinite mass member, means including said mass member for securing said crystal means within said housing with the free end of the crystal means in proximity to said diaphragm and a compressional wave conducting liquid filling the space between the crystal means and the diaphragm.

10. A submarine compressional wave sender and receiver comprising a hollow cylindrical housing open at one end, a compressional wave conducting diaphragm of a phenolic condensation material having a thickness of substantially a quarter wave length at the signaling frequency closing the open end of the housing, a quarter wave length vibratory piezoelectric crystal means loaded at one end by an effectively infinite mass member, means including said mass member for securing said crystal means within said housing with the free end of the crystal means in proximity to said diaphragm and a compressional wave conducting liquid filling the space between the crystal means and the diaphragm.

11. A submarine compressional wave sender and receiver comprising a hollow cylindrical housing open at one end, a compressional wave conducting diaphragm having a thickness of substantially one-quarter wave length as measured

in the material at the signaling frequency, said diaphragm closing the open end of the housing, a longitudinally vibratable element having a length substantially equal to one-quarter wave length as measured in its material at the signaling frequency, said element being loaded at one end by a mass member having a length substantially equal to one-eighth wave length as measured in its material at the signaling frequency, means including said mass member for securing said vibratable element within said housing with the free end of the element in proximity with said diaphragm and a compressional wave conducting liquid filling the space between the vibratable element and the diaphragm.

12. A submarine compressional wave sender and receiver comprising a housing open at one end, a mass element supported therein, a longitudinally vibratable element firmly fixed by one end to said mass element, a diaphragm closing the open end of the housing and positioned with its inner surface close to the free end of said vibratable element, said diaphragm having a thickness of substantially one quarter of a wave length of compressional waves of the signaling frequency in the diaphragm material and having an acoustical impedance which is substantially the geometric mean between the impedance of the vibratable element and the water impedance.

13. An acoustical apparatus comprising in combination a housing open at one end, a diaphragm closing the open end, a mass element entirely supported in and by said housing, electromechanical energy interchanging means including means firmly fixing the same at one end to said mass element and having its other end free in juxtaposed relation with respect to said diaphragm.

14. A closure for use with an acoustical apparatus comprising in combination a cap member having attached thereto a mass element having securely fixed at one end and thereby supporting an electromechanical energy interchanging means and said electromechanical energy interchanging means having a free end acoustically coupled to a vibration propagating medium.
